UNITED STATES PATENT OFFICE.

EMILY L. MERRILL, OF BOSTON, MASSACHUSETTS.

GARMENT-RETAINER.

SPECIFICATION forming part of Letters Patent No. 761,779, dated June 7, 1904.

Application filed January 29, 1904. Serial No. 191,110. (No model.)

To all whom it may concern:

Be it known that I, EMILY L. MERRILL, of Boston, in the county of Suffolk and State of Massachusetts, have invented certain new and 5 useful Improvements in Garment-Retainers, of which the following is a specification.

This invention has for its object to provide an efficient device to aid in adjusting two portions of a lady's dress relatively to each other 10 and to firmly secure the same in such adjusted position.

The invention is especially directed toward the provision of a device for use in connection with a ribbon worn either at the waist as a 15 belt or girdle or at the neck.

The invention consists in the improvements hereinafter described and claimed.

Of the accompanying drawings, forming a part of this specification, Figure 1 represents 20 a perspective view of one form of my improved garment-retainer. Fig. 2 represents a plan view showing the retainer applied to a garment. Fig. 3 represents a section on line 3 3 of Fig. 2. Fig. 4 represents a vertical 25 section on the line 4 4 of Fig. 2. Fig. 5 represents a view showing the effect of belt and neck ribbons when attached to a gown by means of the improved retainer. Fig. 6 represents a simplified form of the retainer. 30 Fig. 7 represents a side view of the same. Fig. 8 represents a view of the form shown in Figs. 6 and 7 with the parts in a different relative position. Fig. 9 represents a view 35 similar to Fig. 6, the attaching member of the device being shortened.

The same reference characters indicate the same parts in all the figures.

Referring first to Figs. 6 to 9, inclusive, the device illustrated in these figures as embodying my invention comprises two principal parts, viz: first, a plate member forming a support and guide for a belt or neck ribbon, and, secondly, an attaching member. *a* represents a substantially flat plate, which may 40 be made of sheet metal or other suitable material and presents a smooth front face when in use, over which the portion of the ribbon which is to be exposed to view passes. At 45 one edge of the plate *a* is formed a perforated 50 enlargement *a'*, which forms a bearing for the

pintle portion of a **U**-shaped fastening member comprising the straight neck portion *c'*, connecting the two sharp-pointed substantially parallel penetrating-pin portions *c c*. The neck *c'*, passing through the bearing or 55 enlargement *a'*, forms a pintle for the hinge connection between the two members. I prefer that the neck *c'* should fit somewhat closely in the enlargement *a'*, as a slight amount of friction between the parts is of some assistance 60 in manipulating the device. The penetrating-pins *c c* are preferably slightly curved, as shown.

In using the device the belt-ribbon *e* is held wrong-side out, with one edge near the point 65 where it is to be fastened. Supposing this point to be just below the waist-line and directly in front, the pins *c c* will be directed upwardly and pushed to nearly or quite their whole length through the ribbon *e* and through 70 the skirt of the gown *d* and into the corset beneath. The pin portions *c c* of the attaching member are so positioned that they will preferably enter the fabric of the corset, one on each side of the front opening, and secure 75 a firm hold. The ribbon is thus firmly secured, particularly against upward movement, which is the result desired at this point. The plate *a* is then turned upwardly to its final position, resting against the skirt, and the 80 the belt-ribbon is also turned upwardly to the position indicated by dotted lines *e'* in Fig. 4 and is further disposed according to the taste of the wearer. It will be noted that by the 85 manner of attachment the retainer is necessarily entirely concealed by the ribbon. The ribbon when folded back into its final position will take the initial shape at its lower portion imparted to it by the plate *a*—that is to say, if the plate *a* is small, and particularly if it 90 is pointed at its lower or outward part, the ribbon being free at other points and restrained by the plate *a* will assume the shape of a belt or girdle pointed at the front or in the position where the retainer has been applied. This embodiment of the invention is particularly well adapted for use in shaping a 95 girdle, and it will be readily understood that by using the retainer at various points a sash or girdle of soft ribbon or silk may be sub- 100

jected to a considerable variation in form and position. By employing four of the devices—viz., two in front, one placed below the waist-line, as described, with the pins *c c* extending upwardly, and the other placed above the waist-line, with the pins *c c* extending downwardly, and two retainers at the back of the gown in similar positions, one below and the other above the waist-line—a girdle may be formed which is widened and pointed at front and back and narrowed as it passes under the arms. The firm engagement of the retainer with the garments of the wearer and the complete concealment of the retainer beneath the ribbon combine to make my improved device a very desirable "girdle-former." It is common to make a shaped girdle by cutting the ribbon or other fabric in several pieces, seaming the pieces together and attaching whale-bones or other stiffening means at the seams to hold the girdle in shape. The method of shaping a girdle by the use of my retainer or girdle-former is much more simple and convenient and is always effective.

To adapt the described form of retainer for a neck-ribbon, I prefer to shorten the pins *c c*, making their length about the same as the height of the plate *a*, as shown in Fig. 9, so that the pins are practically covered by the plate when in position.

In case it is desired, instead of forming a belt or girdle with a sharp point, to give it a round curve I prefer to employ a retainer whose ribbon-guiding plate *a* has a comparatively broad bearing against the fold of the ribbon.

Figs. 1 to 4 illustrate a retainer with a comparatively broad plate *a*. In these figures *bb* represent additional sharp-pointed pins or prongs, which are soldered or otherwise rigidly affixed to the plate *a* and are adapted to engage an edge of the ribbon, but not to enter the fabric of the gown. I find that the provision of the prongs *b* aids materially in adjusting the ribbon over the wide ribbon guide or plate *a* and aid in preventing it from slipping so as to expose the plate.

I have shown in each embodiment of the invention the attaching member as including two pins *c*. This I have found in practice to be desirable; but it is obvious that the invention is not limited to the use of two pins *c*, but may be carried out with one pin or with any desired number.

It will be readily understood that owing to the fact that the outer face of the plate is uniform in the sense that there are no projections therefrom a ribbon which has been turned over said plate across the outer face thereof, as represented by the dotted lines *c'* in Fig. 4, will present a smooth textile surface, giving the same appearance as though

the said ribbon were a portion of a fixed belt or girdle or collar. This device, however, enables a ribbon to be so arranged and displayed wherever wanted, enabling the apparent belt or girdle or collar to be made of any width to suit the taste of the wearer and the width of the ribbon.

I claim—

1. A device of the character described, adapted to secure a ribbon to a garment in the form of a girdle or neck-piece having a widened portion with the ribbon smoothly concealing the device, the said device comprising a plate having a penetrating attaching member hinged thereto at the central portion of one edge of said plate and projecting beyond the opposite edge of the plate to a distance to steady the device and prevent it from being tilted out of the garment by the tension of the ribbon, the central portion of the edge to which the attaching member is hinged projecting beyond the adjacent portions of said edge to enable the ribbon to be smoothly distended or widened at that point, and the portions of the edge each side of the hinge being curved to present no edge protuberances against the ribbon, the outer face of said plate when the latter is turned toward the attaching member being uniform to enable the ribbon to present a smooth textile surface.

2. A device of the character described, adapted to secure a ribbon to a garment in the form of a girdle or neck-piece having a widened portion with the ribbon smoothly concealing the device, the said device comprising a plate having a penetrating attaching member hinged thereto at the central portion of one edge of said plate and projecting beyond the opposite edge of the plate to a distance to steady the device and prevent it from being tilted out of the garment by the tension of the ribbon, the central portion of the edge to which the attaching member is hinged projecting beyond the adjacent portions of said edge to enable the ribbon to be smoothly distended or widened at that point, and the portions of the edge each side of the hinge being curved to present no edge protuberances against the ribbon, the outer face of said plate when the latter is turned toward the attaching member being uniform to enable the ribbon to present a smooth textile surface, the other or inner face of the plate having short prongs to engage the fabric to aid in preventing exposure of the plate by a slipping of the fabric.

In testimony whereof I have affixed my signature in presence of two witnesses.

EMILY L. MERRILL.
